US00D340699S

United States Patent [19]

Chen

[11] Patent Number: Des. 340,699

[45] Date of Patent: ** Oct. 26, 1993

[54] **ELECTRICAL POWER CONTROLLER HOUSING FOR A COMPUTER**

[76] Inventor: **Ching T. Chen**, No. 1, Chu Wei Lane,
Erh Lin Chen, Chang Hua Hsien,
Taiwan

[**] Term: **14 Years**

[21] Appl. No.: **1,228**

[22] Filed: **Nov. 9, 1992**

[52] U.S. Cl. **D13/164; D13/142**

[58] Field of Search **D13/160, 162, 164, 184;**
D14/107, 217, 240; 361/56, 91, 111, 119, 334,
386

[57] **CLAIM**

The ornamental design for an electrical power controller
housing for a computer, as shown and described.

DESCRIPTION

FIG. 1 is a front perspective view of an electrical power controller housing for a computer showing my new design;

FIG. 2 is a front elevational view thereof;

FIG. 3 is a rear elevational view thereof;

FIG. 4 is a top plan view thereof;

FIG. 5 is a bottom plan view thereof;
FIG. 6 is a left side elevational view thereof with the
broken lines included for the purpose of illustrating
environmental elements only and forming no part of the
claimed design; and,

FIG. 7 is a right side elevational view thereof.

FIG. 1

FIG. 4

FIG. 2

FIG. 3

FIG. 6

FIG. 7

FIG. 5
